G. N. BLANCHARD.
HYDROCARBON GENERATOR.
APPLICATION FILED MAY 16, 1921.

1,416,328.

Patented May 16, 1922.

UNITED STATES PATENT OFFICE.

GEORGE N. BLANCHARD, OF SAN FRANCISCO, CALIFORNIA, ASSIGNOR TO EDWIN B. KIMBALL, TRUSTEE, OF SAN FRANCISCO, CALIFORNIA.

HYDROCARBON GENERATOR.

1,416,328.

Specification of Letters Patent. Patented May 16, 1922.

Application filed May 16, 1921. Serial No. 470,050.

To all whom it may concern:

Be it known that I, GEORGE N. BLANCHARD, a citizen of the United States, residing at the city and county of San Francisco and State of California, have invented certain new and useful Improvements in Hydrocarbon Generators, of which the following is a specification.

This invention relates to a hydrocarbon generator of the type set forth and illustrated in Letters Patent No. 1,372,280, dated March 22nd, 1921.

The principal object of this invention is to provide a generator cleaner by the employment of which carbon or other foreign material adhering to the inner wall surface of the generator tube is released therefrom, and is removed from the generating chamber, thus overcoming the objections to burner cleaners now in use wherein the carbon is released from the wall of the generating chamber, but is not removed from within the same but passes through the vapor outlet often clogging the same and materially reducing the efficiency of the generator.

A further object of this invention is to provide a simple form of tubular casing capable of being cheaply manufactured, and from which the cleaning member is capable of endwise removal eliminating the necessity of removing the entire generator from the furnace for purposes of cleaning the same.

A further object is to provide a construction which is without valves, and is therefore capable of being manufactured at little cost, one wherein provision is made for receiving any foreign particles remaining in the generating chamber on the inward movement of the cleaning member thereinto preventing the liability of said particles clogging the vapor outlet.

A further and important object is to incorporate within the cleaning member a cleaning needle for projection into the vapor outlet for freeing the same of foreign substances should such substances collect therein.

With the above mentioned and other objects in view, the invention consists in the novel construction and combination of parts hereinafter described, illustrated in the accompanying drawings, and set forth in the claims hereto appended, it being understood that various changes in the form, propor-

tion, size and minor details of construction within the scope of the claims may be resorted to without departing from the spirit or sacrificing any of the advantages of the invention.

To more fully comprehend the invention, reference is directed to the accompanying drawings, wherein:

Figure 1 is a view in elevation of the preferred embodiment of my invention.

Figure 2 is a vertical sectional view through the casing.

Figure 3 is a full vertical sectional view.

Figure 4 is a transverse sectional view taken on line 4—4 of Figure 3.

Figure 5 is a similar view taken on line 5—5 of Figure 3.

Figure 6 is a like view taken on line 6—6 of Figure 3, and

Figure 7 is a corresponding view taken on line 7—7 of Figure 3.

Referring more particularly to the several views of the drawings wherein like characters of reference designate corresponding parts, 1 indicates a tubular casing open at one end as at 2, and adjacent its opposite end is provided with a transverse wall 3, centrally apertured as at 4. Threaded within the extreme end of the casing 1 is a tip 5 having a vapor outlet orifice 6 in line with the aperture 4. Within the tubular casing, through the open end 2 thereof, is inserted a tubular cleaning member 7, of a diameter less than the inner diameter of the casing, and of a length slightly shorter than that of the casing 1. The cleaning member 7 is threaded on one end, as at 8, to a casing closing nut 9 adapted for threading, as at 10, into the open end 2 of the casing to close the same. The cleaning member 7 is formed with a longitudinal bore 11 extending there-

through, and said bore terminates at the inner end of the cleaning member in an enlarged recess 12; the wall of which is ported, as at 13, and said ports are covered by a filter member 14 preferably in the form of a wire screen which surrounds the end of the member 7. It will be noted that a space is provided annularly of the member 7 between its outer wall and the inner wall of the casing 1, said space affording a generating chamber 15 extending approximately the full length of the interior of the casing 1.

Adjacent its inner end, the cleaning mem-

ber 7 carries a plurality of cleaning elements 16 preferably in the form of rings or discs radially slotted as at 18 providing passages therethrough for the generated vapor in passing from the chamber 15 through the ports 13, recess 12, and outwardly through the vapor outlet 6. The elements 16 are preferably carried by sleeves 19 fitted over the exterior of the member 7, and maintained in spaced relation by a spacing collar 20. One of said elements 16 affords an abutment against which the inner end of the filter member 14 contacts, and said member is maintained in contact with the element 16 by the base of the ferrule 21 threaded over the outer end of the member 7. The ferrule is formed with an overhanging flange 22 frictionally contacting with the inner wall surface of the generating chamber, and said overhanging wall provides a pocket at the inner end of the cleaning member 7 for receiving such foreign substances as may be removed from the interior surface of the generating chamber on the inward longitudinal movement or positioning of the cleaning member within the casing 1; thus reducing the liability of such foreign matter or particles being forced by the vapor pressure into the outlet 6 clogging the same.

30 Mounted within the bore 11, and extending through a similar bore 23 in the nut 9 and adapted for longitudinal reciprocating movement within said cleaning member, is a cleaning rod 24 carrying on its extreme inner end a cleaning needle 25 adapted for projection into the vapor outlet 6 to free the same of foreign material on pressure being applied to the handle 26 of the rod 24.

A coiled spring 27 surrounding the rod 40 and received in a pocket in the outer end of the cleaning member 7 abuts against a flange 28 secured to the cleaning rod and normally maintains outward pressure on the cleaning rod whereby the cleaning needle is normally withdrawn from the vapor outlet 6. A packing 29 surrounds the outer end of the rod 24, and is normally maintained under pressure by an adjusting thimble 30 threaded to the nut 9, and which acts on a follower 45 31 in contact with the packing 29. The follower is maintained under spring tension by the coiled spring 32 positioned between the follower and the thimble 30.

Fuel is admitted preferably into the outer 55 end of the casing 1 through one or more suitably controlled inlets 33.

From this construction it will be observed that the cleaning member 7 is capable of longitudinal withdrawal from the interior of the 60 tubular casing 1, and that during such withdrawal, the elements 16 will scrape the inner surface of the generating chamber and release therefrom such particles of carbon that adhere thereto. The further withdrawal of 65 the cleaning member from the casing will re-

move from the interior of the chamber such released carbon particles, and this cleaning operation is capable of being accomplished without removing the generator from its support, or without removing the generator 70 from its burner, or from the furnace or enclosure within which the burner is positioned.

Having thus described my invention, what I claim as new and desire to secure by Letters Patent of the United States is:—

1. A hydrocarbon generator comprising a tubular casing provided with a fuel inlet leading thereto and having a vapor outlet port leading therefrom, a nut for closing one 80 end of the casing, a tubular generator cleaning member carried by the nut and removably positioned within said tubular casing and affording a generating chamber between its wall and the wall of said casing, said 85 cleaning member being removable longitudinally from the closed end of said casing on the removal of said nut, a carbon cleaning element carried thereby and engaging the inner wall of said casing, a connection between the generating chamber and the vapor outlet port, a reciprocating rod in said tubular member and provided at one point with a cleaning needle, said rod adapted for reciprocation in said tubular member where- 90 by the orifice of said vapor outlet may be freed from foreign substances, and means for normally retaining said rod in position with the needle removed from said vapor outlet. 95

2. A hydrocarbon generator comprising a tubular casing open at its rear end and provided with a fuel inlet leading thereto and a vapor outlet leading therefrom, a tubular 100 cleaning member insertible into and removable from said casing through its open rear end, a nut mounting the member and adapted for securing to the casing to close its rear end, said member affording a generating chamber between its wall and the inner wall 110 of said casing, a connection between the generating chamber and the vapor outlet port, a scraping element carried by the member for engaging the wall of the casing for removing carbon therefrom on the withdrawal 115 of the member therefrom, a cleaning needle carried by the member and adapted for manual projection into the outlet port for cleaning the same, and means associated with the needle for normally maintaining the same 120 removed from the vapor outlet.

3. A hydrocarbon generator including a tubular casing open at its rear end and provided with a fuel inlet, a ported plug closing the opposite end of said casing and affording a vapor outlet, a tubular member insertible into and removable from said casing through its open rear end, said member affording a generating chamber between its wall and the wall of said casing, a clean- 125 130

ing needle carried by said tubular member and removable from the generator therewith, said needle adapted for projection at one end into said vapor outlet for cleaning 5 the same.

4. A hydrocarbon generator including a tubular casing open at its rear end and provided with a threaded inlet, a ported plug closing the other end thereof and providing 10 a vapor outlet, a tubular casing cleaning member insertible into and removable from said casing through its open rear end, and when in position therein having threaded connection with said casing and arranged 15 with one end extended beyond the open end of said casing, a longitudinally movable vapor outlet cleaning member mounted in said tubular member and projecting at one end beyond said tubular member and removable with said member from said casing, and means associated with 20 said vapor outlet cleaning member for normally maintaining the same from contact with said vapor outlet.

5. A hydrocarbon generator comprising a tubular casing provided with a fuel inlet leading thereinto and a vapor outlet leading therefrom, a generator cleaning member normally positioned within said casing and removable intact from the fuel inlet end of 30 said casing for cleaning the inner wall of said casing, said member affording a generating chamber between its wall and the wall of said casing, a cleaning element carried by and extending circumferentially of 35 said member in frictional contact with the inner wall of the casing, and a nut supporting the outer end of the cleaning member and for engaging said casing for retaining 40 the member therein.

6. A hydrocarbon generator comprising a tubular casing open at one end and provided with a fuel inlet leading thereinto and at its opposite end with a vapor outlet leading 45 therefrom, a generator cleaning member removably positioned within said casing through its open end and affording a generating chamber between its wall and the wall of said casing, said generating cleaning 50 member provided at its end with a recess communicating with said vapor outlet, said recess wall provided with a port affording a communication from the generating chamber to the vapor outlet, and a filter 55 through which the vapor passes prior to discharging from said vapor outlet.

7. A hydrocarbon generator comprising a tubular casing open at one end and provided with a fuel inlet leading thereinto and at 60 its opposite end with a vapor outlet leading therefrom, a generator cleaning member removably positioned within said casing through its open end and affording a generating chamber between its wall and the wall of said casing, said generating cleaning 65

member provided at its end with a recess communicating with said vapor outlet, said recess wall provided with a port affording a communication from the generating chamber to the vapor outlet, and a filter member 70 carried by and surrounding said recess wall and through which the vapor traveling through said port passes.

8. A hydrocarbon generator comprising a tubular casing open at one end and provided with a fuel inlet leading thereinto and at its opposite end with a vapor outlet leading therefrom, a generator cleaning member removably positioned within said casing through its open end and affording a generating chamber between its wall and the wall of said casing, said generator cleaning member provided at its end with a recess 75 communicating with said vapor outlet and with a port affording a communication from the generating chamber to the vapor outlet, a cleaning element carried by the generator cleaner in frictional contact with the wall of the generator, said element having a forwardly extended annular wall providing a 80 pocket at the end of said generator cleaning member facing said vapor outlet, and means for removably retaining said cleaning member within the casing and for closing the 85 rear end of said casing.

9. A hydrocarbon generator comprising a tubular casing open at its rear end and provided with a fuel inlet leading thereinto and at its opposite end formed with a vapor outlet, a generator cleaning member normally positioned within said casing through the rear end and when in position affording a generating chamber between its wall and the wall of said casing, a scraping element carried by the cleaning member in 90 frictional engagement with the inner wall of said casing, said cleaning member and element capable of withdrawal longitudinally from said casing through its open rear end whereby carbon or other foreign substances adhering to the inner wall of said casing is scraped therefrom and removed from within the casing through its open end, and a removable means for normally closing the open end of the casing. 95

10. A hydrocarbon generator comprising a tubular casing open at its rear end and provided with a fuel inlet leading thereinto and at its opposite end formed with a vapor outlet, a generator cleaning member removably positioned within said casing and affording a generating chamber between its wall and the wall of said casing, a scraping element carried by the cleaning member in frictional engagement with the inner wall 100 of said casing, said cleaning member and element capable of withdrawal longitudinally from said casing through its open rear end whereby carbon or other foreign substances adhering to the inner wall 105

of said casing is released therefrom and removed from within the casing through its open end on the outward movement of said cleaning member, a vapor outlet cleaning 5 needle associated with the casing and capable of operation to project into the said vapor outlet to free the same of foreign sub-

stances, and a removable means for engaging the casing to normally close the open end of the casing and retain said cleaning 10 member therein.

In testimony whereof I have signed my name to this specification.

GEORGE N. BLANCHARD.
